Inventor,
John Mumma.

United States Patent Office.

CHARLES R. MUMMA, (ADMINISTRATOR OF THE ESTATE OF JOHN MUMMA, DECEASED)
OF MIDDLETOWN, OHIO.

Letters Patent No. 86,095, dated January 19, 1869.

IMPROVED CLOTHES-DRIER.

The Schedule referred to in these Letters Patent and making part of the same:

To all whom it may concern:

Be it known that I, JOHN MUMMA, of Middletown, in Butler county, Ohio, have invented a new and useful Improvement in Clothes-Driers; and I do hereby declare that the following is a full and exact description thereof, reference being had to the accompanying drawings, and to the letters of reference marked thereon.

Figure 1 represents a side elevation of my improved clothes-rack, or drier.

Figures 2 and 3 represent the same in a closed or folded position.

The standards of my clothes-rack consist of two ladders, *a b*, hinged by eye-bolts, near their top, and the two hanging frames *c d* are similarly constructed as ladders, or racks, and are hinged together in the same manner as the standards *a b* are hinged.

The hinged ends of both the standards and racks are bevelled at a suitable angle, and extend a suitable distance beyond the hinges, so as to come in contact squarely when the rack is spread out, and so as to serve as stops to limit the extent to which the rack may be opened.

The hinged self-adjusting frames or wings *c d* are pivoted to the standards at *i i*, on each side of the ladders or standards *a b*.

One of the rounds or rolls *k* extends through the two pairs of ladders, on each side of the rack, to serve as a hinge.

The parts being constructed and hinged together in the manner above described, it is obvious that the movement toward or from each other of the standards or ladders *a b* will cause a like movement of the self-adjusting wings or ladders *c d*.

Any suitable number of rounds, *K*, and pins, *L*, may be attached to the structure, for the purpose of hanging clothing to dry.

I am aware that clothes-racks have been made with

both pairs of ladders, two serving as standards and two also as wings, but these are differently connected and hinged.

My rack, or drier, may be readily adjusted to receive the articles to be dried, by spreading the standards or legs, and the entire structure, with its rounds and pins filled with clothes, may be instantaneously folded, with its contents, to be set aside while the position it may occupy is temporarily required.

Instead of eye-bolt hinges, wire staples may be used, and the projecting ends of the wires which form the staples may pass through separate holes in the rails of the ladders, and be twisted together, to make the hinges fast, when drawn through a proper distance to bring the parts into the relation necessary to cause the bevelled ends of the rails to come squarely together.

It will be observed that the cord or other device connecting the standards or long ladders, to prevent them from spreading too widely, is dispensed with by my invention, as the bevelled ends of the rails, extending beyond the hinges which connect them, serve as stops to limit the extent of their movement in adjusting the rack for use.

Having fully described my improvement in clothes-racks,

What I claim, and desire to secure by Letters Patent, is—

The combination of the ladders *a b* and wings *c d* with bevelled surfaces, and the eye-bolts which serve as stops to limit the expansion of the rack, in the manner and for the purpose specified.

In testimony whereof, I have hereunto set my hand, this 3d day of October, A. D. 1867.

JOHN MUMMA.
